[57] CLAIM

The ornamental design for a stocking, as shown and described.

DESCRIPTION

FIG. 1 is a perspective view of a stocking showing my new design;

FIG. 2 is a top plan view thereof;

FIG. 3 is a front elevational view thereof;

FIG. 4 is a left side elevational view thereof; and

FIG. 5 is a rear elevational view thereof.

The cross hatch shading shown in FIGS. 1-5 is understood to repeat throughout the indicated area.
